[57] CLAIM

The ornamental design for a battery powered light for a door knob, as shown and described.

DESCRIPTION

FIG. 1 is a perspective view of a battery powered lighted for a door knob embodying the design of the present invention;

FIG. 2 is a side elevational view thereof, it being noted that the side opposite is identical to the side shown in FIG. 2;

FIG. 3 is a top plan view thereof, it being noted that the bottom is identical to the top shown in FIG. 3;

FIG. 4 is a front elevational view thereof; and,

FIG. 5 is a rear elevational view thereof.

FIG. 1

FIG. 2

FIG. 3

FIG. 4

FIG. 5
